(57) **CLAIM**

The ornamental design for an automatic double roll tissue feeder, as shown and described.

DESCRIPTION

FIG. 1 is a perspective view of the automatic double roll tissue feeder showing my new design;

FIG. 2 is a perspective view thereof, with the front and top housing removed;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

Broken lines are included for the purpose of illustrating portions of the automatic double roll tissue feeder and form no part of the claimed design.

1 Claim, 8 Drawing Sheets(56)
